OVEN BURNER LIGHTER

Ervin F. Dupuis, Detroit, Mich., assignor to Borg-Warner Corporation, Chicago, Ill., a corporation of Illinois

Application January 25, 1941, Serial No. 375,885

5 Claims. (Cl. 158—115)

The present invention relates to burner lighter assemblies and particularly to an improvement having special application to heavy gas oven burners.

A special problem of lighting has been found to exist in heavy gas burners of the type wherein the flame is fed by a plurality of generally downwardly directed orifices or heavy gas discharge ports. The heavy gas appears to gather in stagnant pockets preventing the necessary mixing of air therewith for ready and efficient combustion.

As a solution to this problem I have found that by providing the necessary means for effecting the proper mixing of a small supply of this gas with air and further effecting the movement thereof upwardly through a primary stack or chimney that the same responds quickly and efficiently to a small lighting flame such as that provided by a match applied at the upper terminal of said primary stack the heat of which is effective to create a pressure differential. This small mixture charge of air and gas upon being lighted supports the necessary initiating flame which travels downwardly through the primary stack in turn igniting the gas discharging through the adjacent downwardly directed discharge port thus effecting the lighting of the entire burner.

It is therefore an object of the present invention to provide means in combination with a heavy gas burner for picking up a small supply of gas therefrom and effecting the requisite movement of the same into mixing contact with the necessary air to constitute a readily combustible charge responsive to a small igniting flame such as a match.

It is a more detailed object to provide a new and efficient arrangement of means for accomplishing the above result which means is simple in operation and inexpensive to manufacture.

Other more particular objects, advantages and uses of my invention will become more apparent from a reading of the following specification taken in connection with the appended drawing forming a part thereof and wherein:

Fig. 1 is an assembly view of a preferred form of my invention showing the burner turned over on its back 180° from the normal position occupied thereby for the purpose of clarity in description;

Fig. 2 is an enlarged broken away plan view showing to advantage the burner and lighter in assembled relation;

Fig. 3 is a vertical section view taken substantially on the line 3—3 of Fig. 2;

Fig. 4 is an enlarged section view of one pre-

ferred embodiment of the auxiliary stack or accelerator structure;

Fig. 5 is a broken away section view corresponding to Fig. 3 but showing the auxiliary stack or accelerator cast as an integral part of the burner;

Fig. 6 is a section view corresponding to Fig. 4 but showing a slightly modified form of accelerating stack;

10 Fig. 7 shows a modified form of flame travel producing construction embodied in the auxiliary stack or accelerator.

Referring in greater detail to the figures of the drawing, there is shown in Fig. 1 a heavy gas burner and lighter assembly therefor. For the purpose of clarity in description the assembly has been turned over on its back through 180° from the position that the same will normally occupy when installed in an oven. The burner proper is indicated generally at 10 and is formed with a plurality of heavy gas discharge ports 11 for feeding the burner flame, these discharge ports being directed generally downwardly when the burner is in its normal position. For the purpose of solving the lighting problem found to exist where heavy gases are employed such for example as those known as liquid petroleum gases and including propane, butane, and others, I have provided a special arrangement of means indicated generally at 12.

Referring particularly to Figs. 2 and 3, a preferred embodiment of my assembly 12 includes generally an upwardly extending primary stack 15 effective upon the application of a flame to the upper terminal thereof to produce a draft; stack 15 has an inlet port 16 at the lower end thereof, and an upper open terminal indicated at 17. The inlet port 16 is disposed in closely adjacent but spaced relation to the side periphery 40 of the burner in the general area of at least one of the downwardly directed heavy gas discharge ports 11, while the upper open end of the stack 17 is located at an elevation above the burner. The result of this arrangement is to produce a draft passing up through stack 15 upon this application of a flame at stack terminal 17. This air in passing through the space between the burner and the stack and into inlet port 16 mixes with the otherwise stagnant heavy gas in this area thus producing a combustible mixture and lifting the same up along the inside of the stack 15 to outlet 17. The flame travels down the stack or chimney 15 with the result that the heavy gas discharging from downwardly directed ports 11 is thus ignited. A port 18 is formed in

the forward wall of stack 15 serving to admit a supplementary air supply into the stream of air and gas rising in the stack to the point of ignition or discharge at 17. The stack 15 may be attached to the burner 10 in any appropriate manner as for example through the medium of radially extending protuberance 19 and attaching screw 20 and oppositely extending protuberance 21 may function to support the forward side of the entire assembly in the oven or burner compartment (not shown).

I have found that the operation and effectiveness of this type of lighter are very much improved by the provision in combination with the above described primary stack of a novel and improved arrangement 30 for effecting the removal of heavy lighting gas from the burner supply chamber 33, mixing the same with air and introducing the mixture into the open lower terminal 16 of the primary stack 15. The arrangement 30 illustrated in Figs. 1 to 4 comprises generally a horizontally extending tubular nipple 31 arranged to be mounted in an opening 32 formed in the wall of the burner 10 and communicating at the inner end with the heavy gas supply within annular burner chamber 33. The opposite end of nipple 31 merges with a generally vertically extending cross-passage 34 defining an auxiliary stack or chimney open at both the top and the bottom thereof. This arrangement 30 functions to withdraw a small supply of the heavy gases from chamber 33 through nipple 31 and to mix the same with the rapidly moving small stream of air being passed up through auxiliary stack 34 at the time a flame is applied at 17 to thus create a difference of pressure and to deliver the same well within the influence of the vertically moving air stream passing into inlet port 16 of primary stack 15. As a matter of fact, some small portion of the heavy gas passing from annular chamber 33 through the horizontal conduit of nipple 31 may drop down through the auxiliary stack and out the lower terminal portion 34 thereof, and in addition some small portion may also pass out through the forward perforation or slit 35 in the vertical wall of the auxiliary stack 30. This is not enough, however, to prevent the proper functioning of auxiliary stack 30 for the purpose intended. The above described limited portion of the gas not immediately elevated by the draft passing up through auxiliary stack 30 may subsequently be picked up by passing into the lower inlet terminal portion 16 of primary stack 15 or some of this gas may remain to be burned in the flashback of the flame subsequent to igniting the mixture by the application of a light at the upper terminal portion 17 of primary stack 15. That portion of the gas remaining immediately in the area of the slit 35 will be burned to define a flame path leading from the upper portion of the auxiliary stack 30 therearound to a point below the auxiliary stack in flame communication with the gas being discharged from downwardly directed discharge ports 11. Any tendency that might otherwise exist for the heavy gas to form relatively dormant or stagnant areas in or about inlet port 16 is thus broken up by the arrangement 30.

It is important to note that the lower open end portion of auxiliary stack 34 is positioned closely adjacent to at least one of the downwardly directed heavy gas discharge ports 11

and further that the accelerator 30 is formed with downward flame travel providing means therein. In Figs. 2, 3 and 4 this flame travel means comprises a coaxial slit 35 in the sidewall 5 of stack passage 34. This slit 35 functions to allow the downwardly traveling flame to pass down the accelerator 30 across the lower end thereof and thus ignite the heavy gas discharging from the associated burner discharge port 11. 10 Turning to Fig. 5, a somewhat modified arrangement is disclosed differing from the showing of Fig. 3 in that the accelerator assembly 30' is formed as an integral part of the burner assembly rather than as a separate element added thereto. The form of my invention shown in Fig. 5 is particularly adaptable to the manufacture of original equipment, while that of Fig. 3 is particularly suitable where my improved accelerator is to be incorporated in the conventional form of burner already manufactured and on the market.

In Fig. 6 there is shown a modified form of auxiliary accelerating stack or chimney 34' the same being in the nature of a venturi for the 15 purpose of still further improving the accelerating characteristics thereof.

In Fig. 7 there is illustrated an alternative embodiment of downward flame travel providing means. In the embodiment of this figure there 20 is provided a series of vertically spaced holes or ports 35'.

From the above it will be made to appear that the success in the operation of the present burner and lighter assembly is explained on the basis 25 of the upward acceleration of the mixed heavy, 30 gas and air to the lighting point 17 and the proper mixture of air for carrying the flame back downwardly to the burning port of the burner from which the main supply of heavy 35 gases is being discharged.

While my invention has a broader application, I nevertheless note that particularly gratifying results on a wide scale numbering in the thousands of successful commercial installations are 40 now in use in oven burner assemblies. The confined, somewhat inaccessible space, and limited air circulation within a range oven appears to lend very outstanding significance to the successful manner in which my invention functions 45 in connection therewith.

While I have disclosed my invention in connection with certain specific embodiments thereof, it is to be understood that these are by way of example rather than limitation and that the 50 scope of my invention is to be defined by the appended claims.

I claim:

1. In a heavy gas burner and lighter assembly therefor including means defining a burner housing formed with a generally annular heavy gas receiving chamber, the lower peripheral wall of said housing being formed with generally downwardly extending gas discharge ports for feeding and directing heavy gas downwardly to a flame therebelow when ignited, said lighter assembly comprising means readily accessible from above said burner housing for accomplishing the lighting of the gas discharged from said ports therebelow, said means comprising means forming a first primary stack including a generally vertically extending bore having a funnel-like open mouth portion disposed adjacent the side peripheral wall of said burner housing adjacent said gas discharge ports but spaced therefrom sufficiently to permit of the air therebelow

as well as the gas being drawn into said stack, said vertically extending bore terminating in an upper open end readily accessible for exposure to a lighting flame, the combination therewith of additional means for directing gas from said annular chamber, mixing the same with air, and delivering the resultant mixture to said funnel-shaped primary stack inlet, said means including a generally vertically extending bore defining a secondary stack, a generally horizontal conduit placing said chamber in communication with said secondary stack intermediate the ends thereof, said vertically extending secondary stack being arranged with the upper terminal portion thereof in the area of said funnel-like open mouth portion of said primary stack, and means defining a perforation in said secondary stack forming a flame travel path for conveying a flame from the upper portion of said secondary stack to the lower portion thereof and hence into position where the same becomes effective to light the gas being discharged from said downwardly directed gas ports in said burner.

2. The combination of a heavy gas oven burner and lighter therefor comprising means defining a burner housing formed with a generally annular heavy gas receiving chamber having a series of downwardly directed gas discharge orifices in the wall of said chamber for feeding gas downwardly to a flame therebelow when ignited, means defining a lighter assembly for said burner including a primary generally vertically extending tubular stack having an open upper terminal portion located at an elevation above the elevation of said burner housing, said primary stack having a generally funnel-shaped lower terminal inlet port disposed closely adjacent to, but spaced from a peripheral side wall portion of said gas chamber to thus allow a free draft of air to pass upwardly into said primary stack inlet port and out of said upper open terminal portion thereof when a lighting flame is introduced at said upper terminal portion thus creating a pressure differential, means effective to direct gas from said gas chamber and discharge the same into the air in the area within said primary stack inlet port to be conveyed upwardly by said air moving through said primary stack upon said introduction of a lighting flame, said means including a generally horizontally extending hollow nipple sealably received in a complementary opening formed in the side wall of said gas chamber, a generally vertically extending secondary draft producing auxiliary chimney or stack intersected by said nipple intermediate the terminals of said auxiliary stack and including a wall formed with a vertically extending slit therein constituting a flame travel path, said secondary stack having a cross-sectional area and a height each of which is only a small fraction of the corresponding dimensions of said primary stack.

3. The combination of a heavy gas oven burner and lighter therefor comprising means defining a burner housing formed with a generally annular heavy gas receiving chamber having a series of downwardly directed gas discharge orifices in the wall of said chamber for feeding gas downwardly to a flame therebelow when ignited, means defining a lighter assembly for said burner including a primary generally vertically extending tubular stack having an open terminal portion located at an elevation above the elevation of said burner housing, said pri-

mary stack having a generally funnel-shaped lower terminal inlet port disposed closely adjacent to, but spaced from a peripheral side wall portion of said gas chamber to thus allow a free draft of air to pass upwardly into said primary stack inlet port and to said upper open terminal portion thereof when a lighting flame is introduced at the discharge outlet of said primary stack to thus create a pressure differential, means effective to direct gas delivery from said gas chamber and discharge the same into the air in the area within said primary stack inlet port to be conveyed upwardly by said air moving through said primary stack, said means including a generally horizontally extending nipple portion adapted to fit tightly in a complementary opening formed in the wall of said gas chamber at an elevation above the elevation of said downwardly directed discharge jets and a generally vertically extending intersecting secondary stack, said stack being further particularly characterized by the formation therein of at least one radially extending orifice at a position generally opposed to the position of intersection of said nipple portion with said stack, said orifice functioning as a flame travel path.

4. In an arrangement of oven burner and lighter therefor adapted to ignite and burn heavy gas, said arrangement including means defining a burner housing formed with a generally annular heavy gas receiving chamber having a series of downwardly directed gas discharge orifices in the wall thereof for feeding gas downwardly to a flame therebelow when ignited, means defining a lighter assembly for said burner including a primary generally vertically extending tubular stack having an open upper terminal portion located at an elevation above the elevation of said burner housing and to which a light may be readily applied for creating a difference in pressure, effecting ignition and a draft through said stack, said primary stack having a generally funnel-shaped inlet port in the lower terminal thereof disposed closely adjacent to, but spaced from the side wall of said gas chamber to thus allow a free draft of air to pass upwardly into said funnel-shaped inlet port of said primary stack and out of said upper open terminal portion thereof upon said ignition, additional means effective to direct gas flow from said gas chamber and cause the discharge thereof into the air in the area within said funnel-shaped inlet port of said primary stack at an elevation above the elevation of said downwardly directed gas discharge orifices to be conveyed upwardly by said air moving through said primary stack, said last named means including a generally horizontally extending conduit communicating at the inner terminal thereof with the interior of said annular gas chamber at a level above that of said downwardly directed discharge jets and a generally vertically extending secondary stack including a wall formed with an opening therethrough constituting a downward flame travel path, said secondary stack having a cross-sectional area and a height, each of which is only a small fraction of the corresponding dimensions of said primary stack, said generally horizontally extending conduit communicating at the outer terminal portion thereof with the interior of said vertical secondary stack.

5. In a heavy gas burner and lighter assembly therefor including means defining a burner housing formed with a generally annular heavy gas receiving chamber, the lower peripheral wall of

said housing being formed with generally downwardly extending gas discharge ports for feeding and directing the heavy gas downwardly to a flame therebelow when ignited, said lighter assembly comprising means readily accessible from above said burner housing for accomplishing the lighting of the gas discharged from said ports therebelow, said means comprising means forming a first primary stack including a generally vertically extending bore having a funnel-like open mouth portion disposed adjacent the side peripheral wall of said burner housing adjacent said gas discharge ports but spaced therefrom sufficiently to permit of the air therebelow as well as the gas being drawn into said stack, said vertically extending bore terminating in an upper open end readily accessible for exposure to a lighting flame, the combination therewith of additional means for directing gas from said annular chamber, mixing the same with air, and delivering the resultant mixture to said funnel-

shaped primary stack inlet, said means comprising a plug-like member formed with a generally vertically extending bore defining a secondary stack, a hollow horizontal stem portion 5 mounted in a complementary opening in the side wall of said gas chamber, said stem placing said chamber in communication with said secondary stack intermediate the ends thereof, said vertically extending secondary stack being arranged 10 with the upper terminal portion thereof in the the open funnel inlet portion of said primary stack, and a narrow vertically extending slit in the wall of said secondary stack defining a flame travel path for conveying a flame from the upper portion of said secondary stack to the lower portion thereof and hence into a position where the same becomes effective to light the gas being discharged from said downwardly directed gas ports in said burner.
